UNITED STATES PATENT OFFICE.

JAMES D. BENBOW, OF AURORA, ILLINOIS, ASSIGNOR TO WESTERN WHEELED SCRAPER COMPANY, OF AURORA, ILLINOIS, A CORPORATION OF ILLINOIS.

ELEVATING GRADER.

Application filed May 24, 1924. Serial No. 715,577.

To all whom it may concern:

Be it known that I, JAMES D. BENBOW, a citizen of the United States, and a resident of Aurora, in the county of Kane and State of Illinois, have invented certain new and useful Improvements in Elevating Graders, of which the following is a specification, reference being had to the accompanying drawings.

This invention relates to improvements in elevating grading machines and more particularly to means for keeping the endless belt of the elevator in properly tightened condition. In these machines the elevator is necessarily of quite considerable length, and owing to the quantity and weight of material deposited upon the endless-belt member and the shocks and jars to which the machine as a whole is subjected as it is moved along over uneven surfaces it has been found quite difficult at times to maintain the belt in properly adjusted position to perform its work to the best advantage. It is the object of my invention to provide means under control of the operator while on the machine for enabling the tension of the belt to be quickly and easily changed at any time that it may seem desirable. This object I accomplish by the means shown in the drawings and hereinafter described. That which I believe to be new is set forth in the claims.

In the drawings,—

Fig. 1 is a rear view of an elevating grader machine embodying the invention;

Fig. 2 is a perspective view of the tension adjusting means, some of the parts that are associated therewith being partly broken away; and

Fig. 3 is an enlarged vertical cross-section taken through the elevator near its outer end.

Referring to the several figures of the drawings,—5 indicates the main frame of a grading machine the rear axle of which machine is indicated by 6, upon the ends of which axle are mounted the rear wheels 7. Pivotally connected at its rear end with the main frame is an elevator, the frame member of which is indicated generally by the numeral 8. This elevator extends laterally from the main frame and is supported by a chain in any desired position, the chain being adapted to be wound upon or un-

wound from a hand-operated drum so as to give the elevator as a whole the desired inclination. The connection of the elevator with the main frame and the means for vertically adjusting it are old and well understood, and therefore no detailed explanation is deemed necessary. As here shown the elevator frame is jointed substantially centrally of its length, the parts being connected together at 9 by means not of my invention and which constitutes the subject-matter of a separate application by one H. D. Hamper filed May 28, 1924, Serial No. 716,427. The endless belt member of the elevator is indicated by 10 (see Figs. 2 and 3), and it passes over a rotatable drum at one end of the elevator frame and a roller or small drum at the other end of the elevator frame, and, as usual, the upper run of the belt receives support at intervals by rollers. The endless belt is driven by means of a sprocket chain 11 that passes over an inner sprocket 12 and an outer sprocket 13, the inner sprocket being driven by means of bevel gears 14 and 15 in the usual manner. The chain, as shown, is supported intermediately of the sprockets 12 and 13 by suitable blocks, such as 16 and 17, that are carried by a bar 18 that is secured to the adjacent face of the elevator frame. 19 indicates curved arms that are secured to opposite sides of the elevator frame and have bolted to their upper ends plates 20 that form members for preventing the material on the belt from falling off at the sides of such belt. 19^a indicates a plow of any desired construction located as usual opposite the lower end of the elevator, and it will be understood that the earth thrown up by this plow will be delivered into the elevator.

21 indicates a shaft upon a projecting end of which the sprocket wheel 13 is non-rotatably secured in any suitable manner, and upon which shaft is also secured one of the drums around which the endless belt member 10 of the elevator passes, such drum being indicated by 22, and it is with the means for adjusting the shaft 21 and the drum thereon the present invention is particularly concerned. As best shown in Fig. 2, the shaft 21 is mounted in bearings 23 that are bolted to the upper flanges and near the outer ends of two parallel slides in the form

of I-beams 24. Each of these I-beams, at a little distance back of the adjacent bearing 23, has its upper flange slidably seated in a grooved guide 25 (see Fig. 3), which is riveted against the lower face of a turned horizontal portion of one of the side bar members of the elevator frame 8. It will thus be evident that with the I-beams free to be moved longitudinally of the elevator frame 10 the drum 22 will be correspondingly moved and hence will affect the tension of the belt 10 that runs over said drum.

Turning now to the means by which the desired sliding movement of the I-beams 24 can be effected at any time by the operator while in position on the machine—26 indicates a rock-shaft extending longitudinally of the main frame 5 of the machine and mounted in suitable bearings on that frame. 20 Keyed or otherwise secured to the rock-shaft is a hand lever 27 having an ordinary spring actuated dog 28 that is normally in engagement with a segmental rack 29 and from which engagement it can be released by a latch lever 30 carried by the lever 27. Secured to the rock-shaft 26 so as to rock therewith are two arms 31, and pivotally connected to each of said arms is a link 32, said links projecting laterally of the frame 5 and in the same general direction as the elevator frame 8. The projecting ends of these links 32 lie at opposite sides of said elevator frame 8 and are pivoted respectively to the upper ends of other arms 33 that, as here shown, are keyed to a second rock-shaft 34 that is journaled in the lower part of the elevator frame 8. Intermediate the end of each arm 33 is pivotally attached a link 35, which links 35 extend along opposite sides 40 of the elevator frame to points near the outer end of such frame and are there connected to the upper ends of short levers 36 which are mounted intermediate of their ends upon a cross-shaft 37 that is supported 45 in the side walls of the elevator frame 8 a short distance back of the drum 22. To the lower end of each of these short levers 36 is pivotally attached the forward end of a link 38. These links 38 extend rearwardly alongside of the movable I-beams 24, and each link 38 at its rear end is pivotally connected to a block 39 that, in the construction shown, is bolted to the outer face of the central web of the adjacent I-beam.

55 From the foregoing description it will be evident that the operator while on the main frame of the machine, can, by a movement of the lever 27 cause a rocking of the shaft 26, and, through the connection therewith of the links, arms and levers described, cause the desired forward or backward movement of the two I-beams 24 in the guide 25, and as such I-beams have mounted on their forward ends the shaft 21 that carries the drum 22 the tension of the belt 10 that runs over

such drum can be changed as desired. Furthermore, it will be evident that the power applied to the shaft 21 will be exactly the same at both its ends, and that such ends will necessarily be moved to precisely the same extent, and hence, if the links at the opposite sides of the elevator are of the same length, as they should be, the shaft 21 and the drum carried thereby can always be maintained exactly at right angles to the sides of the elevator frame, with the result that the power will be applied to the belt in a perfect manner. Owing to the difficulty of having the two sets of links that are at opposite sides of the elevator frame of exactly the same length when secured in position as described, I have formed each of the links at one side of the elevator in two parts and connected such two parts together by a turnbuckle, as is clearly shown in Fig. 2, the turnbuckle uniting the parts of one of the links 32 being indicated by 40, the turnbuckle uniting the parts of one of the links 35 being indicated by 41, and the turnbuckle uniting the parts of one of the links 38 being indicated by 42. It is only necessary to have the links at one side of the frame divided and their parts adjustably connected as by turnbuckles, but it is desirable to so form the links on at least one side for, by such construction it is evident that by means of the several turnbuckles an adjustment of such links can be had that will bring them to the exact length of the one-piece links on the other side, and thereby assure corresponding adjustment of both ends of the shaft 21 and its drum 22.

What I claim as my invention and desire to secure by Letters Patent, is—

1. In an elevating grader, the combination with a main frame, and an elevator frame, of a drum mounted at the outer end portion of the elevator frame, an endless belt traveling over said drum, members mounted to slide longitudinally of the elevator frame and supporting said drum, levers connected with the elevator frame and with said sliding members and operable to adjust the latter longitudinally of the elevator frame, and devices adapted to be actuated from the main frame for operating said levers.

2. In an elevating grader, the combination with a main frame, and an elevator frame, of a drum mounted at the outer end portion of the elevator frame, an endless belt traveling over said drum, members mounted to slide longitudinally of the elevator frame and supporting said drum, levers fulcrumed on the elevator frame, links connecting said levers with said sliding members, and means operable from the main frame and connected with said levers for actuating the same to slide said members longitudinally of the elevator frame.

3. In an elevating grader, the combina-

tion with a main frame and an elevator frame, of a drum mounted at the outer end portion of the elevator frame, an endless belt traveling over said drum, members mounted to slide longitudinally of the elevator frame and supporting said drum, levers fulcrumed on the elevator frame, longitudinally adjustable links connecting said levers with said sliding members, and means operable from the main frame and connected with said levers for actuating the same to slide said members longitudinally of the elevator frame.

4. In an elevating grader, the combination with a main frame and an elevator frame, of a drum mounted at the outer end portion of the elevator frame, members mounted at opposite sides of the elevator frame to slide longitudinally thereof, and supporting said drum, a shaft disposed transversely of the elevator frame and journaled thereon, levers carried by said shaft, links connecting said levers with said sliding members respectively, and means operable from the main frame for actuating said levers.

5. In an elevating grader, the combination with a main frame and an elevator frame, of a drum mounted at the outer end portion of the elevator frame, members mounted at opposite sides of the elevator frame to slide longitudinally thereof, and supporting said drum, a shaft disposed transversely of the elevator frame and journaled thereon, levers carried by said shaft, links connecting said levers with said sliding members respectively, one of said links being longitudinally adjustable, and means operable

from the main frame for actuating said levers.

6. In an elevating grader, the combination with a main frame and an elevator frame jointed intermediately, whereby the outer end portion thereof may swing vertically relatively to the inner end portion thereof, of a drum mounted at the outer end portion of the elevator frame, means slidable longitudinally of the elevator frame for supporting said drum, lever devices connected with said sliding means and with the elevator frame, and operable to move said sliding means longitudinally, arms pivotally mounted on the elevator frame adjacent to the joints thereof and connected with said lever devices for actuating the same, and means operable from the main frame for actuating said arms.

7. In an elevating grader, the combination with a main frame and an elevator frame jointed intermediately, whereby the outer end portion thereof may swing vertically relatively to the inner end portion thereof, of a drum mounted at the outer end portion of the elevator frame, means slidable longitudinally of the elevator frame for supporting said drum, lever devices connected with said sliding means and with the elevator frame, and operable to move said sliding means longitudinally, a shaft disposed transversely of the elevator frame and mounted thereon adjacent to the joints thereof, arms carried by said shaft, means operatively connecting said arms with said lever devices, and means operable from the main frame for swinging said arms.

JAMES D. BENBOW.
